(57) **CLAIM**

The ornamental design for a packing case for lock devices, as shown and described.

DESCRIPTION

FIG. 1 is a front and left perspective view of a packing case for lock devices of a first embodiment, showing our new design;

FIG. 2 is a front and right perspective view of the first embodiment;

FIG. 3 is a front view of the first embodiment;

FIG. 4 is a rear view of the first embodiment;

FIG. 5 is a left side view of the first embodiment;

FIG. 6 is a right side view of the first embodiment;

FIG. 7 is a top view of the first embodiment;

FIG. 8 is a bottom view of the first embodiment;

FIG. 9 is a front and left perspective view of the first embodiment, showing unclaimed lock devices disposed thereon for reference;

FIG. 10 is a front and left perspective view of a packing case for lock devices of a second embodiment, showing our new design;

FIG. 11 is a front and right perspective view of the second embodiment;

FIG. 12 is a front view of the second embodiment;

FIG. 13 is a rear view of the second embodiment;

FIG. 14 is a left side view of the second embodiment;

FIG. 15 is a right side view of the second embodiment;

FIG. 16 is a top view of the second embodiment;

FIG. 17 is a bottom view of the second embodiment; and,

FIG. 18 is a front and left perspective view of the second embodiment, showing unclaimed lock devices disposed thereon for reference.

The broken lines in the drawings depict portions of the packing case for lock devices that form no part of the claimed design. The broken lines shown in FIG. 9 and FIG. 18 depict environmental subject matter and form no part of the claimed design.
